(57) CLAIM

The ornamental design for a symbol display for a gaming device, as shown and described.

DESCRIPTION

This application is related to the following commonly-owned co-pending patent applications: “Gaming Device Having Symbol Displays,” Ser. No. 29/198,753, “Gaming Device Having Symbol Displays,” Ser. No. 29/198,863, and “Gaming Device Having Symbol Displays,” Ser. No. 29/198,864.

FIG. 1 is a front perspective view of the symbol display for a gaming device of our new design, that fragmentary portion of the gaming device shown in phantom is not part of the design sought to be patented and is provided for environmental purposes only; and,

FIG. 2 is a front perspective view of an alternative embodiment of the symbol display for a gaming device of our new design, that fragmentary portion of the gaming device shown in phantom is not part of the design sought to be patented and is provided for environmental purposes only.
